UNITED STATES PATENT OFFICE

KENT A. HAWLEY, OF BALTIMORE, MARYLAND, ASSIGNOR TO LOCKE INSULATOR CORPORATION, OF BALTIMORE, MARYLAND, A CORPORATION OF MARYLAND

INSULATOR SUSPENSION YOKE

Application filed July 10, 1929. Serial No. 377,237.

The invention relates to suspension yokes for a plurality of strings or chains of insulators used for supporting high tension transmission lines.

5 It is well known in the art that it is a common practice to make use of a plurality of strings of insulators where the load is heavy so that in case of breakage of one of the strings, from any cause whatsoever, the load 10 will still be sustained by the others remaining unbroken so that dropping of the conductor will be prevented. Particularly in the case where three strings of insulators are used, considerable difficulty has been encountered owing to the fact that when one string 15 of insulators breaks a severe cantilever or twisting strain will come upon the suspension elements which connect the upper and lower ends of the string of insulators to the yoke 20 arms. This is naturally a serious disadvantage and it is to remedy this condition that I have devised the present invention which has for its general object the provision of a 25 suspension yoke and connections between the same and the insulator strings of such character as to avoid the bringing of any heavy twisting or other similar strains upon the parts, the arrangement being such that the yokes at the top and bottom of the strings 30 may move and accommodate themselves to a new line of pull so that the load will be at least substantially equalized and danger of breaking any of the apparatus avoided.

An important object of the invention is to 35 provide a suspension yoke structure which may include counterpart members at the top and bottom of the strings of insulators so that only one type of yoke will be necessary to effect installation.

40 Another object of the invention is to provide a suspension yoke device and insulator connections or suspension elements engaged therewith which may be very quickly and easily applied and which after application 45 will be positively maintained in place against accidental detachment while capable of having free movement to bring about equalization of strains.

An additional object is to provide a device 50 or structure of this character which will be

simple and inexpensive to make, easy to install, positive in action, efficient and durable in service, and a general improvement in the art.

To the attainment of the foregoing and other objects and advantages, the invention preferably consists in the details of construction and the arrangement and combination of parts to be hereinafter more fully described and claimed, and illustrated in the accompanying drawing in which:

Figure 1 is a side elevation of an installation embodying yokes constructed in accordance with my invention, and

Figure 2 is a top plan view.

Referring more particularly to the drawing the letters A and B designate upper and lower yokes constructed in accordance with the invention and connected with strings of insulators C which are located between them. The upper yoke A is intended to be suspended from a support, as by means of a clevis D or the like while the lower yoke B is intended to carry a conductor holding clamp or the like, not shown. In the present instance there are three strings of insulators in the installation and it is for use in connection with such that my yoke is specially designed. Naturally it is immaterial how the top yoke is suspended and likewise makes no difference what type of conductor clamp is used as such details vary in different installations.

In carrying out the invention I form the yoke A or B as a hub member 10 from which radiate downwardly and outwardly inclined arms 11 which terminate in upwardly directed hooks 12 and which are connected intermediate their ends by transverse brace members 13. The above described parts are naturally formed of metal and are preferably integral in construction, it being customary to make the device by casting. The suspension means is represented as comprising an eye bolt 14 having its shank 15 rotatably engaged within a hole 16 in the hub portion or member 10, the extremity of the shank being threaded and carrying a nut 17 which is preferably cottered at 18 to prevent detachment. At the base of the shank 15 the eye bolt is disclosed as having an angular

portion 19 engaging between upstanding ribs 20 on the hub portion 10. By this means it will be clear that the eye bolt will be held against rotation while the nut is applied but at the same time it is also clear that there may be slight relative rotation of the yoke and eye bolt so that there may be a more complete accommodation to the line of strain in service.

10 The means for mounting the strings of insulators is here shown as comprising elongated loops 21 of substantially elliptical shape, these loops being swingably engaged upon the hooks 12 and being shown as engaged within the clevises of ball head members 22 connected with the caps of the uppermost insulators and within the clevises of socket members 22^a connected with the pins of the lowermost insulators. Of course the 15 lower yoke B is inverted with respect to the upper one. The drawing shows the strings as broken away as they are naturally of indeterminate length depending upon the voltage carried in the transmission lines. To prevent the links 21 from disengagement from the 20 hooks 12, I may provide pins 23 passing through the bight portions of the hooks and extending partly across the open portions, coppers 24 being provided for preventing 25 withdrawal of the pins.

30 In the use of the yoke, it is apparent that they are arranged in opposed relation and connected with the strings of insulators as shown, the uppermost yoke being suspended from a tower or other support and the lowermost one carrying a suitable clamp for holding the conductor. Under ordinary conditions the strain is divided between the three 35 strings of insulators. In the event that one of the strings should break, possibly as the result of a mechanical defect in a casting or the cement which holds the hardware, or as the result of an arc burning away the hardware at an intermediate point, the load will 40 then be sustained by the other two strings. However, when such a contingency occurs it is clear that the yokes will move out of their initial or normal positions as the parts of the 45 installation must accommodate themselves to the line of strain. With the ordinary type of yoke having clevis connections with the insulator strings severe twisting strains and bending strains are set up in the connections. However, with this form of yoke and owing to the suspension of the insulator strings by 50 means of the elongated loops all of the parts can turn, twist or move into different lines without bringing dangerous strains upon and over-taxing the mechanical strength of the parts. This is all due to the freedom of 55 movement as it is apparent that the loops can swing freely and also move laterally to a limited extent with respect to the hooks 12 and as the insulator strings can swing freely upon the links. There is an additional fea-

ture of advantage and that is that the plane in which all the hooks lie is spaced considerably below the connection of the suspension eye bolt 14 with the yoke. This reduces the cantilever strains which come upon the equipment in the event of breakage or other letting go of one of the strings. 70

From the foregoing description and a study of the drawing it will be apparent that I have thus provided a very simple and inexpensive yoke structure by means of which the maximum efficiency in point of equalization and other features is obtained. Installation is very readily and easily effected and the whole arrangement is well calculated to insure great durability. It is thought that the construction, operation and advantages should be readily apparent to one skilled in the art without further explanation. 75

80 While I have shown and described the preferred embodiment of the invention, it should be understood that the disclosure is merely an exemplification of the principles involved as the right is reserved to make all such changes in the details of construction as will widen the field of utility and increase the adaptability of the device provided such changes constitute no departure from the spirit of the invention or the scope of the 85 claims hereunto appended. 90

Having thus described the invention, I claim:

1. A yoke for supporting a plurality of strings of insulators, comprising a hub member provided with suspension means and having a series of inclined diverging arms radiating therefrom and terminating in hooks, horizontal brace elements connecting the intermediate portions of the successive arms and means swingably engaged upon the 100 hooks and adapted for connection with the ends of the insulator strings. 105

2. A yoke for supporting a plurality of strings of insulators, comprising a hub member provided with suspension means and having a series of inclined diverging arms radiating therefrom and terminating in hooks, elongated links swingably engaged upon the hooks and adapted for connection with the ends of the insulator strings, and means partly traversing the open portions of the hooks beyond the links for preventing detachment of the latter. 110

3. A yoke for supporting a plurality of strings of insulators, comprising a hub member provided with suspension means and having a series of inclined diverging arms radiating therefrom and terminating in hooks, elongated links swingably engaged upon the hooks and adapted for connection with the 120 ends of the insulator strings, and pins extending through the hooks and partially obstructing the open portions thereof for preventing withdrawal of the links. 125

4. A yoke for supporting a plurality of 130

- strings of insulators, comprising a hub member having a series of inclined arms radiating therefrom and terminating in upwardly directed portions defining hooks, brace elements extending between and merging into the successive arms, and elongated links swingably engaged upon said hooks for connection with the ends of the insulator strings.
5. A yoke for supporting a plurality of strings of insulators, comprising a hub member having a series of inclined arms radiating therefrom and terminating in upwardly directed portions defining hooks, brace elements extending between and merging into the successive arms, and elongated links swingably engaged upon said hooks for connection with the ends of the insulator strings,
- 10
- 15
- 20
- 25
- 30
- 35
6. A yoke for supporting a plurality of strings of insulators, comprising a hub member having a series of inclined arms radiating therefrom and terminating in upwardly directed portions defining hooks, brace elements extending between and merging into the successive arms, and elongated links swingably engaged upon said hooks for connection with the ends of the insulator strings,
- 20
- 25
- 30
- 35
- said suspension member comprising an eye bolt having its shank passing through said hub member, the bolt having angular portions and the hub member having spaced lugs located outwardly of said angular portions for limiting rotation of the bolt with respect to the yoke.

In testimony whereof I affix my signature.
KENT A. HAWLEY.
